G. Moore Talbert

Attorney

UNITED STATES PATENT OFFICE.

KATE MARCH, OF JEFFERSON CITY, TENNESSEE.

WASHBOARD.

Application filed March 21, 1919. Serial No. 284,033.

To all whom it may concern:

Be it known that I, KATE MARCH, citizen of the United States, residing at Jefferson City, in the county of Jefferson and State 5 of Tennessee, have invented new and useful Improvements in Washboards, of which the following is a specification.

This invention relates to an improvement in wash-boards, and particularly to the 10 vision in a wash-board of a soap-holder, constructed for the convenient retention of the soap therein, and provided with means for draining any fluid which may find its way into the holder back onto the washing 15 surface of the board.

The improved board is provided with a soap-holder opening through the surface or 20 face of the wash board, with the interior dimensions of such holder, slightly in excess of the dimensions of the opening, to provide a soap retaining ledge at the forward edge 25 of the holder. A movable strip is provided which may be arranged to bridge the opening of the soap-holder, or be moved to a position to entirely clear such opening, such strip providing additional means to prevent 30 accidental discharge of the soap from the holder, even when the wash-board is in any unusual position.

The soap holder is formed with a drainage opening or openings in that portion 35 which is approximately lowest when the board is in use, and these openings communicate with openings in the washing surface of the board, to thereby drain all fluid from the holder.

In the accompanying drawings:

Fig. 1 is a view in elevation of the improved wash board.

Fig. 2 is a vertical section of the same.

Fig. 3 is an enlarged broken sectional view showing the retaining strip in operative position with relation to the soap holder.

The improved wash-board is here shown, 45 as comprising legs 1, between which is secured and supported a backing, section 2. The face of such section 2 is provided with the usual corrugated washing section 3; or, if preferred the section 2 may be omitted 50 and the washing section alone used.

The legs 1, are gradually increased in width from a point approximately midway their lengths, and support a top strip 4 which at the forward edge projects beyond 55 the washing surface as at 5, to prevent the

water from splashing over the top of the board when the board is in use.

The board, as is usual, presents a plain section 6 above the corrugated washing section 3, and this section is formed with an 60 opening 7 for the soap holder. This holder is in the form of a box like member 8, secured to the rear face of the section 6, so that the open front of the holder surrounds the opening 7. The length and width of 65 the box is slightly greater than the similar dimensions of the opening, so that when the box is in place, the edge of the opening provides a ledge 9 entirely around the box edge and within the same to prevent accidental discharge of the contained soap, as 70 will be obvious.

A retaining strip 10, preferably of metal 75 is pivoted at 11 to the face of the section 5 of the board, midway the length of the opening 7. This strip is adapted to be moved across the opening 7 when desired, to thus effectively close said opening against the discharge of the soap. A screw 12 receives and temporarily secures the one end 80 of the strip 10, when in soap-retaining position, a pin 13, being secured in the section 5, to receive and hold the free end of the strip 10 when the latter has been moved to an inoperative position.

The bottom of the soap holder is formed 85 with drainage openings 14, and these openings are preferably located adjacent the rear wall of the holder, which is, of course, the lowest part of the holder when the wash-board is in use. These openings 14 communicate, through tube-like channels, or tubes 15 with openings 16 in the face of the corrugated washing section 3, so that water from the soap holder may be drained back 90 onto the washing surface, to prevent undue waste of the soap.

The arrangement of the pivoted end of the retaining strip, and of the means for temporarily securing the free end of such strip in soap-retaining relation to the holder, as well as the drainage openings 16 in the washing section 3, are to be constructed and arranged, as shown, with particular regard not only to their stated function, but 100 so that the clothing rubbed over the washing section 3 will not be injured.

The invention having been described, what is claimed as new and useful is:

A wash board formed above the washing 110

surface with an opening, a box like holder secured to said board and in said opening, a retaining strip having a pivotal connection at one terminal with the board above the opening and swingable to and from a position spanning the said opening, a pin carried by the board above the said opening and to one side of the pivotal connection of the retaining strip and adapted to enter a perforation formed in one end of the latter

to hold the said strip in a position unobstructing the said opening, and a screw engaged with the board and which may be inserted through the perforation in the retaining strip to secure the latter in spanning relation to the said opening. 15

In testimony whereof she affixes her signature.

KATE MARCH.
